UNITED STATES PATENT OFFICE

153,187

DESIGN FOR A SHIRT

Anna Spector, Chicago, Ill.

Application February 18, 1948, Serial No. 144,571

Term of patent 14 years

(Cl. D3—25)

To all whom it may concern:

Be it known that I, Anna Spector, a citizen of the United States, residing at Chicago, in the county of Cook and State of Illinois, have invented a new, original, and ornamental Design for Shirt, of which the following is a specification, reference being had to the accompanying drawing, forming part thereof.

with the front flap buttoned.

Figure 3 is a rear elevational view of the shirt.

I claim:

The ornamental design for a shirt, as shown.

ANNA SPECTOR.
